UNITED STATES PATENT OFFICE.

HIRAM EDRINGTON, OF TURNERS STATION, KENTUCKY.

CAR-FENDER.

1,252,558.

Specification of Letters Patent.

Patented Jan. 8, 1918.

Application filed October 30, 1917. Serial No. 199,347.

To all whom it may concern:

Be it known that I, HIRAM EDRINGTON, a citizen of the United States, residing at Turners Station, in the county of Henry and

5 State of Kentucky, have invented certain new and useful Improvements in Car-Fenders, of which the following is a specification.

My invention relates to guards or fenders for railway cars, trolley cars and street cars.

10 The object of my invention is to produce a guard or fender for inclosing the sides of cars beneath the floors thereof to prevent persons from falling under the cars and their wheels. Another object of my inven-

15 tion is to produce a device of the character described, adapted to be adjustably secured upon the sides of cars and capable of being adjusted to different heights from the ground. A further object thereof is to pro-

20 duce a fender of said character, adapted to be vertically slid upon suitable supports upon the side of a car; and a still further object of my invention is to produce a more simple, cheap and efficient device of said

25 character than has heretofore been constructed.

To these ends, my invention includes the combination and arrangement of component parts to be hereinafter described and more 30 particularly pointed out in the claims.

In the accompanying drawings, in which like reference characters indicate similar parts,—

Figure 1 is a side view of my invention 35 showing the fenders in lowered position;

Fig. 2 is a similar view showing the fenders in raised position;

Fig. 3 is an end view of one side of a car equipped with my fenders;

40 Fig. 4 is a vertical sectional view taken on the line 4—4 of Fig. 1;

Fig. 5 is a detail view of a portion of the side of a car with the fender plates removed;

45 Fig. 6 is a horizontal sectional view of a portion of a side plate, and

Fig. 7 is a detail sectional view showing the headed bolt on which my side plates slide.

50 Referring now to the drawings, 1 indicates the side of a car upon which is secured a plurality of vertically disposed bars 2 which depend somewhat below the lower edge of the side. Said bars are secured

thereon by the bolts 3 having the screw- 55 threaded ends and nuts 4 on the inner end and the enlarged head or button 5 on the outer end.

As shown in the drawings, a plurality of plates 6 are carried on said bars and adjustably secured thereon by the heads 5 of the bolts 3 before mentioned engaging in the slots 7.

For the purpose of securing said plates in desired position and to permit them to be 65 held in vertical adjustment, I provide the looped rod 7' secured on the side of the car as by bolts 8. Said looped rod embraces the fender plates to permit them to slide up and down therein and the outer member of the 70 rod is provided with a plurality of ratchet teeth 9 into which the pawl 10 carried on the face of the fender plates may be engaged when the fender plates are raised from their lowered positions. The outer end of said 75 pivoted pawl is counter-weighted to throw the engaging end into contact with the ratchet teeth on the bar.

As shown in the drawings each of said fender plates is provided with shoulders or 80 lugs 11 on each side of the looped rod 7' to act as guides when the fender is raised and lowered.

From the foregoing description, and by reference to the accompanying drawings, it 85 will be appreciated that my fender plates when carried in lowered positions, will inclose the lower parts of a car and completely prevent a person falling beneath the wheels thereof, and yet will permit the fender 90 plates to be readily raised for the purpose of gaining access beneath the car to make adjustments or repairs that might be required.

Having thus described my invention what 95 I claim as new, and desire to be secured by Letters Patent is—

1. A car fender comprising a plurality of vertically disposed bars secured upon the sides of a car, a plurality of vertically disposed plates having vertical slots therein, headed bolts passing through said slots to secure said plates on the sides of a car, and means for securing said plates in raised and lowered positions. 100

2. A car fender comprising a plurality of vertically disposed bars secured upon the sides of a car, a plurality of vertically dis-

posed plates having vertical slots therein, headed bolts passing through said slots to secure said plates on the sides of a car, a looped rod carried on the side of a car intermediate of the vertical bars provided with ratchet teeth on the edge thereof, a pawl pivotally carried on said fender plate to engage said teeth and guide lugs on said plate

on each side of said looped rod, substantially as described.

In testimony whereof I affix my signature in the presence of two witnesses.

HIRAM EDRINGTON.
